DESIGN.

—o—
A. B. CAMERON.
PANEL.

No. 20,413.

Patented Dec. 16, 1890.

UNITED STATES PATENT OFFICE.

ALLAN B. CAMERON, OF WILLIAMSPORT, PENNSYLVANIA.

DESIGN FOR A PANEL.

SPECIFICATION forming part of Design No. 20,413, dated December 16, 1890.

Application filed November 22, 1890. Serial No. 372,375. Term of patent 14 years.

To all whom it may concern:

Be it known that I, ALLAN B. CAMERON, of Williamsport, Lycoming county, Pennsylvania, have invented and produced a new and original Design for Panels, of which the following is a specification, reference being had to the accompanying photograph, showing my said design and forming part thereof.

My design consists in a series of triangular elevations, as A, radiating from a center. The said elevations have rounded surfaces, and their outer edges are beveled or inclined and are disposed in a circle, producing the appear-

ance of a series of scallops B. The face of the panel is concave, except at the center, at which there is a conical elevation C. The surface of the cone gradually curves into the concavity of the panel-face.

I claim—

The design for a panel, substantially as herein shown and described.

ALLAN B. CAMERON.
